(57) **CLAIM**

The ornamental design for a holy water sprinkler, as shown and described.

DESCRIPTION

FIG. 1 is a front elevational view of the sprinkler;
FIG. 2 is a perspective side view of the sprinkler;
FIG. 3 is a rear elevational view of the sprinkler;
FIG. 4 is a top view of the sprinkler; and,
FIG. 5 is a bottom view of the sprinkler.
The black shown in FIGS. 1-4 is known to uniformly represent hair.
